(57) **CLAIM**

The ornamental design for the hose reel cart, as shown and described.

DESCRIPTION

FIG. 1 is a front left plan view of a hose reel cart;
FIG. 2 is a front right perspective view of the hose reel cart;
FIG. 3 is a front left perspective view of the hose reel cart taken from above showing the unclaimed hose in the reeled position, and the unclaimed cable in the reeled position;
FIG. 4 is a front view of the hose reel cart;
FIG. 5 is a right side view of the hose reel cart;
FIG. 6 is a rear view of the hose reel cart;
FIG. 7 is a left side view of the hose reel cart;
FIG. 8 is a top view of the hose reel cart;
FIG. 9 is a bottom view of the hose reel cart;
FIG. 10 is a rear right plan view of the hose reel cart;
FIG. 11 is a front left plan view of the hose reel cart; and,
FIG. 12 is a front view of the hose reel cart shown with unclaimed subject matter in broken lines in an alternate environment of use.

The broken lines shown in the drawings depicts environmental subject matter only; the broken lines form no part of the claimed design.
